UNITED STATES PATENT OFFICE.

JOSEPH M. BROKAW, OF GRAND RAPIDS, MICHIGAN.

FENCE-POST.

SPECIFICATION forming part of Letters Patent No. 254,194, dated February 28, 1882.

Application filed March 18, 1881. (No model.)

To all whom it may concern:

Be it known that I, JOSEPH M. BROKAW, of Grand Rapids, in the county of Kent, and in the State of Michigan, have invented certain new and useful Improvements in Fence-Posts; and I do hereby declare that the following is a full, clear, and exact description thereof, reference being had to the accompanying drawings, and to the letters of reference marked thereon, making a part of this specification.

This invention relates to certain improvements in fence-posts; and it has for its objects to provide a post which will be simple and inexpensive in construction, which will possess great strength and durability, and which can be securely embedded in the ground. These objects I attain by the devices illustrated in the accompanying drawings, in which—

Figure 1 represents a front view of my improved fence-post, and Fig. 2 a vertical sectional view of the same, and Fig. 3 a top view of the post.

The letter A indicates the base of the post, which consists of a cubical or other shaped block, preferably of brick, although it may be constructed of other material, such as stone or the like. The forward face of the block or brick is formed with a groove or seat for the upright B, which is secured to said block or brick by means of a screw-bolt and nut, as indicated by the letter C. The said upright B extends below the base or block, so as to take se-

curely into the ground, the base being embedded therein with its upper surface flush with the surface of the ground. The upright also 35 at its lower end may be bent horizontally, as indicated by the letter D, so as to form an "anchor," so as to more securely hold the post in place.

The letter E indicates a series of apertures 40 formed at suitable intervals through the upright, by means of which fence-rails, wires, or other like barriers may be properly secured to the post. The upright is preferably constructed of iron, although other material may be used. 45

Prior to my invention fence-posts have been provided with a base or foundation, which has been placed in the ground, and hence I do not claim such feature, broadly.

Having thus described my invention, what 50 I claim, and desire to secure by Letters Patent, is—

A fence-post composed of a base having a grooved seat, and the upright B, located in said seat and provided with a right-angled bend at 55 its lower end, substantially as and for the purposes specified.

In testimony that I claim the foregoing I have hereunto set my hand this 12th day of March, 1881.

JOS. M. BROKAW.
